UNITED STATES PATENT OFFICE.

REUBEN NICHOLLS, OF PHILADELPHIA, PENNSYLVANIA.

FEEDER FOR ORGAN-BELLOWS.

SPECIFICATION forming part of Letters Patent No. 246,971, dated September 13, 1881.

Application filed April 28, 1881. (No model.)

To all whom it may concern:

Be it known that I, REUBEN NICHOLLS, of Philadelphia, in the county of Philadelphia and State of Pennsylvania, have invented a new and useful Improvement in Piston Bellows-Feeders for Organs, whereby escape-valves in the piston trunk or cylinder may be automatically opened when the bellows becomes fully distended.

10 I am aware it is not new to prevent over-pressure in the bellows by an automatically-opened escape-valve; but such valves have, so far as I know, heretofore been generally located in the bellows, when so located, and 15 the sudden partial collapse of the same when the escape-valve is opened causes a slight fluctuation in the feed to the pipes, and is therefore objectionable.

My invention corrects this defect by permitting 20 the escape of surplus wind from the piston-chamber, and therefore avoids all disturbance of the wind in the bellows and wind-trunks and chests.

My invention therefore consists, first, in a 25 piston-feeder for organ-bellows provided with automatic escape in or near the ends of the piston chamber or trunk, whereby the surplus wind is permitted to escape when the bellows becomes fully distended, and without checking 30 the motion of the piston; second, in the system of levers and connecting-rods whereby the distention of the bellows causes the escape-valves in the piston-trunk to open and permit the escape of the surplus wind.

35 That others may fully understand my invention, I will particularly describe it, having reference to the accompanying drawings, wherein—

Figure 1 is a longitudinal section of my feeder 40 and organ-bellows. Fig. 2 is a transverse section of the same.

A is the organ-bellows, constructed, weighted, and communicating with wind-trunks F in the usual way. B is the piston-trunk, and C is the 45 piston moving therein, being actuated by proper and efficient power. D D are the induction-ports, covered by valves in the usual way. E E are the eduction-ports, through 50 which the wind is forced from the piston-trunk to the wind-trunk F, whence the conveyances G conduct and discharge it into the bellows A. These parts are all constructed as usual.

At the bottom of the piston-trunk B, I make two or more ports, H, and cover the same with valves I, which, when closed, prevent the escape 55 of any wind through the ports H H. These are the escape-valves in the piston-trunk. If they are opened, the wind forced by the piston will simply escape by way of port I, instead of being forced into trunk F. There are many 60 ways of causing said valves to open automatically; but the method which I prefer is by means of the compound levers J, K, and L, which are collectively and simultaneously operated by the bellows when it reaches the 65 period of complete distention. The levers J K are pivoted to standards b d, and at their proximate ends they are in contact, so that the depression of one may compel the depression of the other. The lever L is placed in a position 70 transverse to the levers J and K, and at its free end it rests upon the proximate ends of those levers. At its center said lever L is pivoted to a standard, e, and at its outer end it is connected to the top of the bellows by a 75 tension-rod, M, whereby said outer end of the lever L will be drawn up when the bellows approaches maximum distention, and by being so drawn up the proximate ends of lever J and K will be depressed. The outer or free 80 ends of said levers J and K are connected to the valves I I, respectively, by tension-rods rr, so that when the bellows A approaches complete distention, by means of the levers described or their equivalent, the valves I I will 85 be automatically opened, and the surplus wind will be permitted to escape without checking the movement of the piston or disturbing the wind in the wind-chest S or bellows.

Having described my improvement, what I 90 claim as new is—

1. In combination with the bellows and wind-trunk of an organ and a reciprocating feeder therefor, one or more automatic valves in said feeder, adapted to be operated substantially 95 as described, whereby, when the bellows approaches complete distention, said valves will be opened and permit the surplus wind to escape from the feeder without checking the motion of said feeder or piston, and without 100 disturbing the wind in the bellows or wind-trunk and chests.

2. A reciprocating piston-feeder, B, and an organ-bellows, A, connected therewith, com-

bined with escape-valves I, arranged within the feeders, connected with said bellows, and adapted to operate in the manner described, so that the said valves will be opened by the 5 movement of said bellows when the latter approaches complete distention and permit the surplus wind to escape from the feeder.

3. The piston-trunk B, provided with the piston C and the escape-valves I, combined

with the bellows A and levers J K L, arranged 10 substantially as shown and described, and connected by tension-rods with said bellows and escape-valves, respectively, substantially as set forth.

REUBEN NICHOLLS.
